[57] CLAIM

The ornamental design for a filmstrip projector, substantially as shown and described.

DESCRIPTION

FIG. 1 is a perspective view of a filmstrip projector showing our new design in the closed configuration.

FIG. 2 is a perspective view of a filmstrip projector showing our new design in the open configuration.

FIG. 3 is a top plan view thereof in the open configuration.

FIG. 4 is a bottom plan view thereof in the closed configuration.

FIG. 5 is a side elevational view thereof in the open configuration.

FIG. 6 is an elevational view thereof in the open configuration of the side opposite to that in FIG. 5.

FIG. 7 is a front elevational view thereof in the closed configuration.

FIG. 8 is a rear elevational view thereof in the open configuration.

*Fig.1.**Fig.3.**Fig.2.**Fig.4.**Fig. 5.**Fig. 7**Fig. 6.**Fig. 8.*
